ART OF FORMING BAG BOTTOMS

Kenneth A. Rusch, Milwaukee, Wis., assignor to Milprint, Inc., Milwaukee, Wis., a corporation of Delaware

Application April 23, 1956, Serial No. 580,050

9 Claims. (Cl. 150—5)

The present invention relates generally to improvements in the art of packaging, and relates more particularly to the provision of an improved commodity bag and the method of producing the same.

A primary object of the invention is to provide an improved commodity receiving bag which is strong and durable in construction and has an exceedingly strong and effective leak-proof bottom seal and which may moreover be readily produced in quantity and at low cost in accordance with a novel method.

It has heretofore been common practice to commercially produce commodity bags from webs of heat sealable ribbon stock by first folding the advancing web into flat tubular formation, then longitudinally heat sealing overlapped edge portions to complete the tube, thereafter severing the tube into sections of desired length, and by subsequently either sealing the walls directly to each other transversely across an end of the successive sections by application of heat and pressure or by folding an end of each section back upon itself and finally applying heat and pressure to the four thicknesses of the folded over portion to thereby heat seal the end of each tube section and provide the bag. While these prior heat sealing methods and the bags produced thereby have proven quite satisfactory as applied to packaging materials of certain types capable of being readily heat sealed while withstanding relatively high temperatures for sufficient periods of time to permit firm bonding and strong seals, many films which possess highly desirable characteristics for packaging purposes have an extremely critical range in which heat may be applied safely and without resultant damage to the material, and these films therefore cannot all be readily adapted for use as commodity bags in accordance with prior production methods of heat sealing.

It is therefore a more specific object of the present invention to provide an improved commodity bag structure and method of producing the same which obviate the objections and disadvantages attendant prior known structures and production methods.

Another specific object of this invention is to provide a commodity bag formed of heat sealable material and having a novel and improved highly efficient leak-proof and sift-proof bottom seal formed with the aid of heat and pressure.

Another specific object of my invention is to provide an improved method of commercially producing commodity bags and of effecting the bottom or transverse end seals therein by a relatively simple and unique heat sealing operation.

Still another specific object of my present invention is to provide an improved commodity bag comprising, a flat tubular body, one end of the body being folded back upon one of the side walls thereof and being secured to the adjacent side wall by a heat seal extending transversely thereacross, and the folded end portion beyond the heat seal being free of attachment to the adjacent side wall with both thicknesses of the free portion thereof being secured to each other.

2

An additional specific object of the present invention is to provide an improved method of producing commodity bags, which comprises, forming a flat tubular body from a sheet of heat sealable material, transversely folding an end of the body back upon one of its side walls, sealing the folded portion adjacent the fold line through both thicknesses thereof to the adjacent body side wall by application of heat and pressure, and securing both thicknesses of the free end of the folded portion beyond the seal to each other by application of heat and pressure only to the folded portion.

These and other specific objects and advantages of the invention will become apparent from the following detailed description.

15 A clear conception of the features constituting the present invention and of the several steps of the improved method of producing a typical commodity bag in accordance therewith may be had by referring to the drawing accompanying and forming a part of this specification 20 wherein like reference characters designate the same or similar parts in the various views.

Fig. 1 is a fragmentary side view diagrammatically illustrating typical apparatus for facilitating production of commodity bags in accordance with the improved 25 method and showing a flat tube of suitable packaging material being transversely severed;

Fig. 2 is another fragmentary diagrammatic side view just prior to the transverse folding operation;

Fig. 3 is a similar fragmentary diagrammatic side view 30 showing the start of the folding operation;

Fig. 4 is still another fragmentary side view showing the end of the tube folded back over the upper guide plate;

Fig. 5 is a fragmentary diagrammatic side view just 35 prior to the heat sealing operation;

Fig. 6 is a similar view with the folding plate withdrawn and showing the tube being transversely heat sealed to form the bag bottom;

Fig. 7 is an enlarged fragmentary perspective view 40 illustrating the same step as shown in Fig. 5 in which the end of the tube is folded and is about to be transversely sealed; and

Fig. 8 is a similarly enlarged perspective view of a typical flat commodity bag produced in accordance with the 45 improved method and embodying the improved bottom construction.

While the invention has been particularly shown and described herein as being especially advantageously applicable in the production of plain square cut commodity bags formed of thin heat sealable films which are highly sensitive to heat and require great care in the control of the heat during sealing operations, it is not desired or intended to thereby unnecessarily restrict or limit the invention since the improvements may also be 55 utilized to good advantage in the production of gusset type bags formed of any heat sealable materials. It is furthermore contemplated that certain specific descriptive terms used herein shall be given the broadest possible interpretation consistent with the disclosure.

60 In accordance with my present improved method of producing commodity bags having the novel and improved bottom construction, I initially fold a continuous ribbon or web of thin flexible heat sealable film material along spaced longitudinal lines and seal the overlapping 65 longitudinal edges thereof in a customary manner to form a flat tubular body which may be severed into desired lengths. Next, an end portion of the tubular body is folded back upon one of its side walls along a transverse fold line, and the body side walls are internally separated 70 adjacent to the fold line while the folded portion remote from the fold line is separated from the adjacent body side wall. Then, sealing heat and pressure is applied trans-

versely across the folded portion adjacent to the fold line and in the area in which the side walls are internally separated to thereby secure both thicknesses of the folded portion to each other and to the adjacent side wall only, and sealing heat and pressure is likewise applied transversely across the folded portion remote from the fold line and in the area in which the folded portion is separated from the adjacent side wall to thereby secure both thicknesses of the free end of the folded portion only to each other.

In the commercial exploitation of the improved bag producing method, the flat tubular body 10 and longitudinal side seam 11 thereof may be formed with the aid of commercially available apparatus and in a well known manner requiring no further description, and the tube may be transversely severed into desired lengths with the aid of suitable cooperating knives 12, 13 as shown in Fig. 1. To maintain the side walls 14, 15 of the tubular body 10 internally separated, the tube is advanced about a separating and backing plate or internal former 16 and directly beneath an external separating and backing plate 17 which also serves as a guide plate during the transverse folding operation, the plate 17 being reciprocable from a position shown in Figs. 2 to 4 inclusive wherein the forward edge thereof is in approximate alinement with the forward edge of the former 16 to a position such as shown in Figs. 5 and 6 in which the plate 17 is retracted to a position somewhat rearwardly of the forward edge of the former 16. For folding the end portion 18 of the tube 10 back upon the side wall 14, a suitable folding plate 19 may be provided which is vertically and laterally movable, as shown in Figs. 2 to 5, to fold the portion 18 about the edges of the cooperating plates 16, 17 to a position above the side wall 14, whereupon the folding plate 19 may be withdrawn and the plate 17 may be retracted as described to a position between the folded portion 18 remote from the fold line 20 and the side wall 14 of the tube. The final sealing operation may then be performed with the aid of a heat sealing bar 21 having laterally spaced legs 22, 23 extending transversely across the tube, the bar 21 being vertically movable into contact with the folded portion 18 of the tube, as shown in Figs. 5 and 6, with the leg 22 thereof cooperating with a backing pad 24 on the internal separating plate 16 to apply sealing heat and pressure transversely across the portion 18 adjacent to the fold line 20 and the leg 23 thereof cooperating with a backing pad 25 on the separating plate 17 to apply sealing heat and pressure transversely across the portion 18 remote from the fold line 20.

The commodity bag thus formed comprises, in general, a flat tubular body 10 having an end portion 18 thereof folded back upon the side wall 14 along a transverse fold line 20, the folded end portion 18 being secured through both thicknesses thereof only to the adjacent side wall 14 of the body adjacent to the fold line 20 as by the heat seal 26 extending transversely across the body, and the folded end portion 18 remote from the fold line 20 beyond the heat seal 26 being free of attachment to the adjacent side wall 14 and having both thicknesses of the free portion secured only to each other by a separate transverse heat seal 27.

From the foregoing detailed description, it is believed apparent that the present invention contemplates the provision of a bag-like receptacle having an improved strong, durable and leak-proof bottom structure adapted to be produced in accordance with a novel and improved production method. The bags produced by the method possess full capacity and the bottom is effectively sealed transversely thereacross by means of the heat seal 26 which firmly unites both thicknesses of the folded bottom portion 18 and one adjacent side wall 14 to thereby give full capacity to the bag, and the additional heat seal 27 firmly unites the free end of the portion 18 through both thicknesses of the material entirely independent of both of the bag walls to thereby give added assurance as to

the leak-proof and sift-proof qualities of the bag. By means of the improved method, the heat and pressure required to form the bottom seal is considerably reduced because of the fact that a minimum number of thicknesses of material are operated upon thus obviously reducing the amount of heat required to effectively seal the desired areas. Furthermore, the improved method may be carried out in a continuous manner and is readily adapted for commercial production of the improved bag units. The method enables quantity production of bags from all types of heat sealable materials even though certain of these materials may have a very critical range within which heat may be safely applied, and it is likewise effective in the production of commodity bags from materials which are not necessarily extremely critical or sensitive to high sealing heats.

It should be understood that it is not desired or intended to limit this invention to the exact steps of the production method or to the precise details of construction of the bags herein shown and described, since various modifications within the scope of the appended claims may occur to persons skilled in the art to which this invention pertains.

I claim:

- 25 1. The method of producing commodity bags, which comprises, forming a flat tubular body from a sheet of heat sealable material, transversely folding an end of the body back upon one of its side walls, sealing the folded portion adjacent to the fold line through both thicknesses thereof to the adjacent body side wall by application of heat and pressure, and securing both thicknesses of the free end of the folded portion beyond the seal to each other by application of heat and pressure only to the free end of the folded portion.
- 30 2. The method of producing commodity bags, which comprises, initially forming a flat tubular body from a sheet of heat sealable material, transversely folding an end of the body back upon one of its side walls, sealing the folded portion adjacent to the fold line through both thicknesses thereof to the adjacent body side wall by application of heat and pressure, and securing both thicknesses of the free end of the folded portion beyond the seal to each other by application of heat and pressure only to the free end of the folded portion.
- 35 3. The method of producing commodity bags, which comprises, initially forming a flat tubular body from a sheet of heat sealable material, transversely folding an end of the body back upon one of its side walls, sealing the folded portion adjacent to the fold line through both thicknesses thereof to the adjacent body side wall by application of heat and pressure, and securing both thicknesses of the free end of the folded portion beyond the seal to each other by application of heat and pressure only to the free end of the folded portion.

- 40 4. The method of producing commodity bags, which comprises, initially forming a flat tubular body from a sheet of heat sealable material, transversely folding an end of the body back upon one of its side walls, sealing the folded portion adjacent to the fold line through both thicknesses thereof to the adjacent body side wall by application of heat and pressure, and securing both thicknesses of the free end of the folded portion beyond the seal to each other by application of heat and pressure only to the free end of the folded portion.
- 45 5. The method of producing commodity bags, which comprises, initially forming a flat tubular body from a sheet of heat sealable material, transversely folding an end of the body back upon one of its side walls, sealing the folded portion adjacent to the fold line through both thicknesses thereof to the adjacent body side wall by application of heat and pressure, and securing both thicknesses of the free end of the folded portion beyond the seal to each other by application of heat and pressure only to the free end of the folded portion.
- 50 6. The method of producing commodity bags, which comprises, initially forming a flat tubular body from a sheet of heat sealable material, transversely folding an end of the body back upon one of its side walls, sealing the folded portion adjacent to the fold line through both thicknesses thereof to the adjacent body side wall by application of heat and pressure, and securing both thicknesses of the free end of the folded portion beyond the seal to each other by application of heat and pressure only to the free end of the folded portion.
- 55 7. The method of producing commodity bags, which comprises, initially forming a flat tubular body from a sheet of heat sealable material, transversely folding an end of the body back upon one of its side walls, sealing the folded portion adjacent to the fold line through both thicknesses thereof to the adjacent body side wall by application of heat and pressure, and securing both thicknesses of the free end of the folded portion beyond the seal to each other by application of heat and pressure only to the free end of the folded portion.
- 60 8. The method of producing commodity bags, which comprises, initially forming a flat tubular body from a sheet of heat sealable material, transversely folding an end of the body back upon one of its side walls, sealing the folded portion adjacent to the fold line through both thicknesses thereof to the adjacent body side wall by application of heat and pressure, and securing both thicknesses of the free end of the folded portion beyond the seal to each other by application of heat and pressure only to the free end of the folded portion.

- 65 9. The method of producing commodity bags, which comprises, initially forming a flat tubular body from a sheet of heat sealable material, transversely folding an end of the body back upon one of its side walls, internally separating the body side walls adjacent to the folded end, applying heat and pressure to the folded portion adjacent to the fold line through both thicknesses of the folded portion and the adjacent body side wall to thereby secure both thicknesses of the folded portion to each other and to the adjacent side wall only, separating the free end of the folded portion beyond the seal from the adjacent body side wall, and applying heat and pressure to the free end of the folded portion to thereby secure both thicknesses thereof only to each other.
- 70 10. The method of producing commodity bags, which comprises, initially forming a flat tubular body from a sheet of heat sealable material, transversely folding an end of the body back upon one of its side walls, sealing the folded portion adjacent to the fold line through both thicknesses thereof to the adjacent body side wall by application of heat and pressure, and securing both thicknesses of the free end of the folded portion beyond the seal to each other by application of heat and pressure only to the free end of the folded portion.
- 75 11. The method of producing commodity bags, which

comprises, initially forming a flat tubular body from a sheet of heat sealable material, folding an end portion of the body back upon one of its side walls along a transverse fold line, internally separating the body side walls adjacent to the fold line while separating the folded portion remote from the fold line from the adjacent body side wall, applying heat and pressure to the folded portion adjacent to the fold line to thereby secure both thicknesses of the folded portion to each other and to the adjacent side wall only while also applying heat and pressure to the folded portion remote from the fold line to thereby secure both thicknesses thereof only to each other.

6. A commodity bag comprising, a flat tubular body having an end portion thereof folded back upon itself to close the end of the body, said folded end closure portion being secured to the adjacent side wall of said body by a heat seal extending transversely thereacross, and said folded end closure portion beyond said heat seal being free of attachment to the adjacent side wall with both thicknesses of said free portion being secured to each other, the opposed side walls of said body being free of attachment.

7. A commodity bag comprising, a flat tubular body having an end portion thereof folded back upon itself, said folded end portion being secured only to the adjacent side wall of said body by a heat seal extending transversely thereacross, and said folded end portion beyond said heat seal being free of attachment to the adjacent side wall

with both thicknesses of said free portion being secured only to each other.

8. A commodity bag comprising, a flat tubular body having an end portion thereof folded back upon itself along a transverse fold line, said folded end portion adjacent to said fold line being secured only to the adjacent side wall of said body by a heat seal extending transversely thereacross, and said folded end portion remote from said fold line and beyond said heat seal being free of attachment to the adjacent side wall with both thicknesses of said free portion being secured only to each other.

9. A commodity bag comprising, a flat tubular body having an end portion thereof folded back upon itself along a transverse fold line, said folded end portion adjacent to said fold line being secured through both thicknesses thereof only to the adjacent side wall of said body by a heat seal extending transversely thereacross, and said folded end portion remote from said fold line and beyond said heat seal being free of attachment to the adjacent side wall with both thicknesses of said free portion being secured only to each other by a separate heat seal.
